UNITED STATES PATENT OFFICE.

ALBERT WITTIG, OF BERLIN, GERMANY.

METHOD OF PRODUCING METALLIC VANADIUM.

No Drawing.

Application filed May 7, 1924. Serial No. 711,742.

To all whom it may concern:

Be it known that I, ALBERT WITTIG, a citizen of Germany, and a resident of Berlin, Germany, have invented Improvements 5 in Methods of Producing Metallic Vanadium, of which the following is a specification.

My invention relates to an improved method of producing vanadium and vanadium 10 alloys from vanadic acid, ferric vanadate and other vanadium compounds.

The production of metallic vanadium from vanadic acid, ferric vanadate and several other vanadium compounds is old 15 and in particular the method of manufacturing vanadium from the stated vanadium compounds by thermic reduction with the aid of aluminium is known to persons versed in the art as the so-called Goldschmidt thermic method.

I have discovered, after much study and research, that I can greatly improve the aforesaid thermic reduction method and considerably increase the output in vanadium 25 thereof by treating the vanadium compound, prior to the reducing process or any preliminary stages thereof, with substances, containing nitrogen preferably, with gaseous or liquid ammonia—solution of ammonia—or with ammonium salts, and without oxidizing efforts, at an elevated temperature.

In some cases, especially if ammonium salts are employed I heat a mixture of a triturated vanadium compound and ammonium salt to a red heat, prior to the reducing operation and I then proceed in the usual way to reduce the metal according to the said thermic method.

As far as I see, probably vanadium nitrids

form by treating the vanadium compound with nitrogen containing substances. It has been found that by such preliminary treatment the output in metallic vanadium will increase by 14 p. c.

I have not attempted to explain all of the details of the method of reducing the vanadium compounds preliminarily treated with a nitrogen containing substance, according to my invention, for it will be understood by those, who are versed in the art and to whom this specification is addressed that the said method is practically carried out in the usual way.

What I claim is:—

1. The method of producing metallic vanadium from vanadium compounds, consisting in treating the vanadium compound, at an elevated temperature, with substances, containing nitrogen and without oxidizing effort and subjecting the thus treated vanadium compound to the known thermic reducing process.

2. The method of producing metallic vanadium from vanadium compounds, consisting in treating the vanadium compound, at an elevated temperature, with an ammonium compound, and subjecting the thus treated vanadium compound to the known thermic reducing process.

3. The method of producing metallic vanadium from vanadium compounds, consisting in heating the vanadium compounds, together with an ammonium salt to a red heat, and subjecting the thus treated vanadium compound to the known thermic reducing process.

In testimony whereof I have signed my name to this specification.

ALBERT WITTIG.
